UNITED STATES PATENT OFFICE.

JOSEF SUBERT AND JOSEPH SUBERT, JR., OF OAK PARK, ILLINOIS.

HUMIDIFIER FOR HOT-AIR FURNACES.

Application filed July 22, 1926. Serial No. 124,148.

This invention relates to humidifiers and has special reference to devices of this character for use with hot air furnaces.

One of the objects of our invention is to provide a humidifier to be placed within the jacket of a hot air furnace so as to moisten or humidify the air that is heated by the furnace for delivery to remote areas to be heated.

10 Another object of our invention is to provide air humidifying means within the furnace jacket occupying a comparatively small space but having a large surface area which is kept moist by an automatically controlled 15 water conveying means.

A further object of the invention resides in novel automatic means for regulating the flow of water into the humidifier.

A still further object finds embodiment in 20 the provision of a novel valve for controlling the flow of the water into the humidifier.

It is also an object of the invention to provide a compact and novel humidifying unit 25 including novel structural features which render the assembly and installation of same at comparative low cost.

With these and other objects in view, our 30 invention consists in the novel combination, construction and arrangement of the parts and members shown in one preferred embodiment in the accompanying drawings, described in the following specification, and particularly pointed out in the appended 35 claim.

Referring to the illustrations: Fig. 1, is 40 a diagrammatic elevation of a hot air furnace, in part section, showing an application of our invention;

Fig. 2, is a front elevation of a humidifier unit embodying our invention;

Fig. 3, is a vertical section of same;

Fig. 4, is an enlarged section taken on line 4-4 of Fig. 2, showing a plan view of the 45 inlet valve controlling bucket;

Fig. 5, is an enlarged cross section taken on line 5-5 of Fig. 2, showing a plan view of the bracket for supporting the humidifier tube, also a plan view of the bracket supporting the pivot for the valve operating 50 links;

Fig. 6, is an enlarged vertical section taken on line 6-6 of Fig. 2, showing a vertical section of the valve and a vertical section of 55 the upper end of the humidifier tube; and,

Fig. 7, is a cross section taken on line 7-7

of Fig. 6, showing the water distributing plate at the upper end of the humidifier tube.

Referring to the illustrations in detail, 10 designates a hot air furnace having the usual 60 hot air chamber 11 provided between the outer furnace casing 12 and the furnace wall 13. The humidifier unit is here shown in a preferred construction comprising a pair of angle iron structural supports 14 connected 65 at their upper and lower ends with bars 15 and provided intermediate their ends with brackets 16 and 17. The structural frame is adapted for support on the outer face of the furnace casing 12, as shown in Figs. 1 and 3. 70 The humidifier tube 18 is preferably of cylindrical formation with the wall thereof perforated and the lower end terminates in conical formation, while the upper end of the 75 humidifier tube is closed with a water inlet casting 19. The humidifier tube 18 is filled with granular material such as small gravel or stones to provide a comparatively large 80 surface which is kept in a moistened condition and always exposed to the action of the hot air within the chamber 11. The lower end of the humidifier tube 18 is provided with a collar 18^A to provide a support on the bracket 17.

The water inlet 19 comprises a circular 85 casting having a horizontal inlet passage 19^A and a vertical discharge passage 19^B. A separate distributor plate 19^C is connected to the bottom of the inlet 19 by means of screws 19^D and by means of a plurality of openings 90 19^E distributes the water over the upper surface of the granular material within the 95 humidifier tube. The nipple 20 is provided with a pair of threaded ends 20^A and 20^B and with a longitudinal passage 20^C. The threaded end 20^A extends through the upper end of the humidifier tube into the inlet casting 19 and the other threaded end 20^B extends through the outer furnace casing 12 into the valve 21, thus providing a support for 100 the upper end of the humidifier tube and for the valve 21. The valve outlet 21^A, it will be observed, communicates with the passage 20^C to permit an unobstructed flow of water 105 into the passages 19^A and 19^B of the inlet 19.

The water inlet 22 communicates at one end with a water supply 23 which may be provided with an emergency valve 24 and at the other end is connected to the valve plug 21^B which is screw-mounted into the valve casing 21. A 110 reciprocating cylindrical plunger 21^C is provided within the casing 21 and carries at its

upper or inner end a leather washer 21^D which forms a seat for the lower or inner end of the valve plug 21^B. It will be apparent that when the plunger 21^C is pressed upwardly with its washer 21^D against the lower end of the plug 21^B, the discharge passage 21^A of the valve will be closed so that no water can enter the humidifier tube. The lower end of the plunger 21^C is pivotally connected with a link 25, the lower end of which link is pivotally connected to the lever arm 26. The lever arm 26 is pivotally mounted on the support 27 which is fixed to the bracket 16. The outer end of the lever arm 26 is pivotally connected with a second link 28 having its lower end pivotally connected to the plate 29. A weight 30 is pivotally supported on the lower end of the plate 29, and the plate 29 is rigidly mounted between the bent portion of the rocker frame 31.

The frame 31 comprises a single bar, the ends of which form pivotal supports for the water bucket 32. A pin 33 extends through the arms of the frame 31 into the angle iron supports 14.

By reference to Fig. 3, it will be observed that the outer furnace casing 12 is provided with a pair of slots 12^A for the bracket 17, and with an opening 12^B large enough to permit the insertion and removal of the bucket 32. A suitable closure or gate 34 is provided to cover the opening 12^B, and the closure 34 is provided with a pair of vertical slots 35 for the arms of the yoke 31.

It will now be readily apparent that we have provided an efficient humidifier for hot air furnaces, the operation of which may be briefly described as follows: The water passing through the inlet valve 21, through the nipple 20, into the inlet casting 19, is distributed by means of the plate 19^C, and flows through the mass of granular material within the humidifier tube 18, thereby thoroughly moistening the entire mass, and the excess water is permitted to discharge through the conical discharge end of the humidifier tube into the bucket 32. When the bucket 32 is filled to a predetermined level, the weight of the water will tilt the rocker frame or yoke 31 and cause an upward movement of the links 28 and 25 to close the valve 21 by means of the plunger washer 21^D engaging or seating against the bottom of the valve plug 21^B.

As the temperature of the air surrounding the humidifier tube 18 is increased, the level 55 of the water in the bucket will be gradually lowered due to evaporation, and the valve 21 will be gradually opened to allow more water to flow into the humidifier tube, thus positively maintaining the inner core of the granular material in a moistened condition. At a certain high or maximum temperature, almost all of the water in the bucket 32 will be 60 evaporated and the valve 21 will be practically wide open to continually moisten the mass, but as the temperature in the hot air chamber 11 lowers, the bucket will receive the excess or unevaporated water from the humidifier tube and thus gradually close the valve 21. In this manner, the granular material in the humidifier tube is continually maintained in a moistened condition to moisten the air within the furnace chamber 11.

The weight 30 is provided as a counter-weight for the bucket 32 and for the purpose 75 of positively maintaining the valve 21 in open position. The weight of a predetermined quantity of water in the bucket 32, however, is sufficient to overcome the pull of the weight 30 and to close the valve 21.

We claim:

A humidifier for hot air furnaces having an outer casing, comprising a vertical tubular container having perforated sides and bottom and granular material within said container; means for mounting said container in an upright position within said outer casing, a water supply outlet at the upper end of said container for depositing water within said container and moistening said granular material, a valve for controlling the flow of water through said supply outlet, a movably mounted bucket located below and adjacent to the bottom of said container and adapted to receive the excess of water passing into 90 and through said container and not retained by said granular material, and means interconnected with said valve and movably mounted bucket for automatically controlling the closing and opening of said valve and 95 regulate the flow of water within said container and upon said granular material and in the bucket.

In witness whereof we affix our signatures.

JOSEF SUBERT.
